(57) CLAIM

The ornamental design for a slatwall section, as shown and described.

DESCRIPTION

FIG. 1 is a front perspective view of a slatwall section showing my new design;

FIG. 2 is a bottom edge view of FIG. 1;

FIG. 3 is a top edge view of FIG. 1;

FIG. 4 is a left edge view of FIG. 1;

FIG. 5 is a front side view of FIG. 1;

FIG. 6 is a back side view of FIG. 1;

FIG. 7 is a second embodiment of a slatwall section showing my new design;

FIG. 8 is a bottom edge view of FIG. 7;

FIG. 9 is a top edge view of FIG. 7;

FIG. 10 is a left edge view of FIG. 7;

FIG. 11 is a front side view of FIG. 7;

FIG. 12 is a back side view of FIG. 7;

FIG. 13 is a third embodiment of a slatwall section showing my new design;

FIG. 14 is a bottom edge view of FIG. 13;

FIG. 15 is a top edge view of FIG. 13;

FIG. 16 is a left edge view of FIG. 13;

FIG. 17 is a front side view of FIG. 13; and,

FIG. 18 is a back side view of FIG. 13.

The slatwall section is broken in the center to indicate indefinite length.
